UNITED STATES PATENT OFFICE.

JOHN E. SLOVEY, OF KENNEDY, CALIFORNIA.

ANTICREEPER RAIL PLATE.

Application filed April 17, 1922. Serial No. 552,777.

To all whom it may concern:

Be it known that I, JOHN E. SLOVEY, a citizen of the United States, residing at Kennedy, in the county of Shasta and State of California, have invented certain new and useful Improvements in Anticreeper Rail Plates, of which the following is a specification.

The present invention relates to tie plates 10 designed to effectively hold railroad rails from creeping or moving longitudinally.

The object is to provide a simple, practical or thoroughly effective device which can be cheaply manufactured and can be easily 15 placed in position and removed, permitting a corresponding positioning and removal of the rail.

In the accompanying drawings:—

Figure 1 is a plan view of a portion of a 20 rail showing two of the tie plates in position thereon,

Figure 2 is a vertical sectional view on the line 2—2 of Figure 1,

Figure 3 is a perspective view of the plate, 25 Figure 4 is a perspective view of the holding wedge.

In the embodiment disclosed the plate consists of a body 5 provided in its upper side with a recessed seat 6 of the width of the 30 rail base 7. It will be noted by reference to Figures 2 and 3 that the side walls 8 of this seat are vertical and consequently a rail can be vertically dropped into place and removed. Spike-receiving openings 9 are 35 formed in the plate on one side of the seat and directly adjacent thereto so that the heads of spikes driven through said openings will overlap the rail base, as illustrated in Figure 2. On the opposite side of the seat 40 there is a spike receiving opening 10 directly adjacent to the seat, so that a spike driven therethrough will have its head overlying the rail base, and between said opening 10 and the opposite side of the plate there is 45 formed a tapered socket 11 having its inner side opening into the seat 6 and designed to receive a plain faced holding wedge 12. This socket has its bottom in the same plane as the bottom of the seat 6. A second spike- 50 receiving opening 13 is formed in the plate outside the said socket 11.

With this construction, the plate can be placed upon a tie and the rail dropped into the seat. When properly positioned the 55 spikes can be driven and afterwards the

wedge 12 inserted and tightened by blows against its exposed end. It will be evident that when the wedge is in place any tendency of the rail to creep will simply tighten the wedge and react and thus form a firmer 60 binding action that will effectively lock the rail.

Obviously these plates can be made with right and left wedges, as illustrated in Figure 1 and may be reversed so as to hold the 65 rail irrespective of the direction in which it may tend to creep or move longitudinally.

From the foregoing, it is thought that the construction, operation and many advantages of the herein described invention will 70 be apparent to those skilled in the art, without further description, and it will be understood that various changes in the size, shape, proportion and minor details of construction may be resorted to without departing from the spirit or sacrificing any of 75 the advantages of the invention.

Having thus fully described my invention, what I claim as new, and desire to secure by Letters Patent, is:—

An anti-creeper tie plate for railroad rails, comprising a body having a recessed rail base receiving seat in its upper side substantially the width of the rail base and having substantially vertical side walls that permit the vertical removal and replacement of the rail base, said body being also provided with spike-receiving openings on opposite sides of said seat and sufficiently close on both sides to cut through the side 85 walls of the seat and permit the heads of the spikes to overlie the base flange, said body on one side being provided with a tapered socket that terminates at its smaller end substantially at one of the said spike-receiving openings and said socket furthermore having its bottom in the plane of the bottom of the seat, and a plain sided wedge 90 slidably engaged in said socket and adapted to bear against the adjacent edge of the rail base and stop short of the spike-receiving opening, said tie plate further having a spike-receiving opening on the outer side of the tapered socket.

In testimony whereof, I affix my signature 105 in the presence of two witnesses.

JOHN E. SLOVEY.
